UNITED STATES PATENT OFFICE.

JOHN LINES, OF WATERBURY, CONNECTICUT, ASSIGNOR TO THE SCOVILL MANUFACTURING COMPANY, OF SAME PLACE.

DESIGN FOR A LAMP-BURNER BODY.

SPECIFICATION forming part of Design No. 29,670, dated November 15, 1898.

Application filed October 24, 1898. Serial No. 694,485. Term of patent 14 years.

To all whom it may concern:

Be it known that I, JOHN LINES, a citizen of the United States, residing at Waterbury, in the county of New Haven and State of Connecticut, have invented and produced a certain new, useful, and original Design for a Lamp-Burner Body, of which the following is a full, clear, and exact description.

Referring to the accompanying drawings, which form part of this description, Figure 1 is an elevation of a lamp-burner body, showing my new design. Fig. 2 is a vertical section taken at right angles to the plane of Fig. 1.

As shown in the drawings, the leading or material feature of my design consists of the external contour or configuration of the dome or cone *a*, gallery *b*, and base *c*. The foot of

the gallery has the knurled edge *d*, and the upper edge *e* of the base is knurled. The fingers of the gallery are cut out in ornamental pattern, and the cove of the base is also cut out in ornamental pattern.

Having described my invention, what I claim as new, and desire to secure by Letters Patent, is—

The design for a lamp-burner body, substantially as herein shown and described.

In testimony whereof I have hereunto set my hand this 21st day of October, A. D. 1898.

JOHN LINES.
